METHOD AND APPARATUS FOR CIRCULATING AND HUMIDIFYING THE AIR IN A REFRIGERATING ROOM AND FOR DEFROSTING

Carl S. Zedlik, Minneapolis, Minn.

Application August 25, 1933, Serial No. 686,714

4 Claims. (Cl. 62—6)

This invention relates to a refrigerating apparatus, and particularly to a refrigerating apparatus which comprises a room cooled by a plurality of conduits to which a cooling medium is supplied. In most establishments where meat and other perishable products are kept, a chamber is provided which is usually cooled by a plurality of pipes or conduits through which a cooling medium is circulated by an artificial refrigerating means. There is usually a partition between said pipes or conduits and the main portion of the chamber in which the articles to be refrigerated are placed. It has been found that with such an arrangement a heavy coating of ice accumulates on the conduits and it is necessary at more or less frequent intervals to chop this ice from the conduits. The accumulation of this ice lowers the cooling efficiency of the conduits and its removal is necessary. Such conduits frequently have moisture thereon to such a degree that water drips from the coils making a wet and slimy condition in the cooling chamber.

It has also been found that meat and other products will not keep properly in certain parts of the cooling room. The humidity also often is at a low point so that the meat dries out. Of recent times it has been considered quite necessary and beneficial to have a high degree of humidity in the cooling room so that the meat is kept in fresh and moist condition.

It is an object of this invention to provide a simple and efficient device for removing the ice from the cooling coils, furnishing moisture to the cooling chamber to maintain the humidity at a high point and to effect a uniform distribution of air in said cooling chamber.

It is a further object of the invention to provide a means for causing air to flow over said cooling conduits at one side of a partition which is usually provided between said conduits and the main portion of said chamber, whereby said air will melt the ice from said conduits, carry the moisture into said chamber and cause a uniform distribution of air in said chamber.

It is another object of the invention to provide a cooling chamber having a plurality of cooling conduits for cooling the same with a partition between said conduits and the main portion of said chamber together with means for directing air from the upper portion of said chamber over said conduits at one side of said partition, said air passing around one end of said partition into said chamber, means also being provided to cause intermittent operation of said last mentioned means at regular intervals.

It is more specifically an object of the invention to provide a cooling chamber, a plurality of conduits carrying a cooling medium for cooling the same, a partition between said conduits and the main portion of said chamber, a casing adjacent one end of said partition adapted to direct air at one side thereof over said conduits and into said chamber, whereby ice will be removed from said conduits, moisture will be supplied to said chamber and a uniform distribution of air effected, means preferably being provided to cause an intermittent operation of said last mentioned means at regular intervals.

These and other objects and advantages of the invention will be fully set forth in the following description made in connection with the accompanying drawing, in which like reference characters refer to similar parts throughout the several views and in which:

Fig. 1 is a view in vertical section through a cooling chamber taken substantially on line 1—1 of Fig. 2; and

Fig. 2 is a horizontal section through the cooling chamber taken substantially on line 2—2 of Fig. 1.

Fig. 3 is a diagrammatic sectional view of the controlling switch and associated parts.

Referring to the drawing, a chamber is shown comprising side walls 5 and a top wall 6. These walls are usually made rather thick and contain insulating material. Within said chamber is a partition 7 having its ends spaced from the wall 6 and from the bottom of said chamber, and between said partition and one side wall are disposed conduits 8, illustrated as extending horizontally substantially throughout the width of said chamber, which conduits will be connected to a refrigerating apparatus adapted to circulate a cooling medium therethrough. In most establishments which sell or handle meat such apparatus is usually installed in the basement. Such refrigerating apparatus and cooling conduits are now well known and need not further be described. One side wall 5 is shown as provided with a door 5a mounted on the hinges 9 and held shut by a latch 10. A plurality of hooks 11 are shown secured in and projecting from the side walls 5 and partition 7, such as used to support meat.

In accordance with this invention, a casing 12 is provided and while this casing may be variously located, in the embodiment of the invention illustrated, it is shown as disposed adjacent the top wall 6 and somewhat adjacent one side wall 5. Said casing is shown as being supported

by a plurality of brackets 13, and is shown as an open-ended conduit of considerable size and while the same may take various shapes, it is illustrated as being cylindrical in form. Casing 12 is disposed so that one open end is directed toward conduits 8 and adjacent one end of partition 7. Said casing is also shown as sloping upwardly from said end and, as shown in Fig. 2, said end is farther from the adjacent side wall than the 10 other end.

A fan 14 is disposed in casing 12 having the usual driving motor 15 of the electrical type secured thereto, said motor and fan being secured to casing 12 by the small brackets 16. A pair of 15 conductors 17 and 18 are shown extending to motor 15, one of which is controlled by a switch shown as disposed in casing 19 mounted on wall 6. Said switch comprises a rotating element 20 having contact segments 20a shown as three in 20 number and substantially equal in extent to the spaces therebetween. Said switch also comprises a stationary contact member 20b adapted to be engaged at intervals by the members 20a. Member 20 is mounted upon a shaft 21 which will preferably be connected to the shaft of a minute hand of a clockwork mechanism 19a so that member 20 is revolved regularly and makes one revolution in an hour. Shaft 21 is electrically connected to conductor 18 as indicated in Figs. 2 and 3.

In operation, the clockwork mechanism will be operated and switch member 20 revolved. When one of the segments 20a is in contact with contact member 20b, the circuit through motor 15 will be closed and current will be supplied to said motor to drive fan 14. When said segments 20a are not in engagement with contact 20b the circuit of motor 15 is broken and said motor and fan 14 are not operated. Air will be drawn into the 40 upper end of casing 12 by said fan and said air will be directed out at the lower end of said casing to one side of partition 7, downwardly over and between the cooling conduits 8 and will pass out into the chamber below the bottom of partition 7. The air drawn into casing 12 is taken from the upper portion of the chamber where the warmest air accumulates. When a contact segment 20a is not in engagement with contact member 20b, fan 14 will be stopped and will remain stopped until 50 another member 20a engages contact member 20b. Fan 14 will thus be started and stopped at regular intervals and while these intervals may be varied, in the embodiment of the invention illustrated, the fan will be operated for ten minutes and then stopped for ten minutes.

The described operation accomplishes three very important things. Any ice which has accumulated on the coils or conduits 8 will be melted and removed by the air directed over said conduits. The moisture from the melted ice is taken up by the air and carried into the chamber and this maintains the humidity in said chamber at a high point. The circulation of air effects a uniform distribution of air in all parts of the chamber so that meat keeps just as well in one part as in another. The intermittent operation of the fan is quite important. It has been found in practice that if the fan is run continuously, the humidity drops and there is a drying effect on the meat. The fan being idle for a period allows the warmer air to accumulate at the top of the chamber and this air when directed downwardly over the conduits readily melts the accumulated ice therefrom. With the device in operation only a light layer of frost accumulates on the pipes or

conduits 8 which is the most desirable condition. There is no dripping from the conduits 8, and, as stated, the moisture from these conduits is carried into the cooling chamber by the air and maintains the humidity therein at a high point. 5

It will be understood that the cooling medium is supplied to the coils 8 by a refrigerating apparatus driven by an electric motor. This motor is operated intermittently the same being controlled by a thermostat disposed in the chamber to be 10 cooled which chamber is illustrated as having the side walls 5 and the top wall 6. When fan 14 starts after a period of rest the air from the top of the chamber which is the warmest air moves down over the coils 8 and, when the cooling medium is not being circulated in said coils, this air melts the accumulated frost or ice from the coils. The coils thus become moist and the air moving over the moist coils is effectively washed. This results in the extraction of odors from the air 20 and in keeping the air in fresh condition even after the chamber has been closed for a long period as at night or on a holiday. As stated it has been necessary heretofore to chop heavy accumulations of ice from conduit 8. The action 25 of the air in applicant's device prevents a heavy accumulation of ice so that this operation is entirely eliminated. The device has received long tests and records have been kept of the humidity. These records show that the humidity is quite 30 uniform and that the temperature remains the same in all parts of the chamber. The latter fact is due to the fan 14 which circulates the air at regular intervals.

The device is quite simple and can be easily 35 and quickly installed in the small refrigerating rooms now used by meat stores and at small expense. The device has been found to have great utility in cooling the chamber in a display counter where meat and other articles are cooled. 40 In such an installation the bottom of the chamber in the counter forms the partition between the chamber and cooling conduits. As stated, the device has been amply demonstrated and tested in actual practice and found to be very 45 successful and efficient.

It will, of course, be understood that various changes may be made in the form, details, arrangement and proportions of the parts, without departing from the scope of applicant's invention, 50 which generally stated, consist in a device capable of carrying out the objects above set forth, in the parts and combinations of parts disclosed and defined in the appended claims.

What is claimed is:—

1. A refrigerating device having in combination with a chamber to be cooled, a plurality of conduits in said chamber to which a cooling medium is supplied at intervals for cooling said chamber, means for directing air over said conduits and circulating the same in said chamber, and chronometric means for starting and stopping said last mentioned means at regular intervals and independently of the temperature in said chamber, whereby ice at times is melted and removed from said conduits, moisture is carried by said air to said chamber to maintain a high humidity therein and a uniform distribution of air in said chamber is effected. 65

2. In combination with a chamber of comparatively large size, a partition adjacent one wall of said chamber and spaced from the top and bottom thereof and a plurality of refrigerating coils between said wall and partition to which a cooling medium is intermittently supplied to main- 75

tain substantially a certain temperature in said chamber, of means adjacent the top of said chamber and partition for moving air from the top of said chamber downwardly over said coils beneath 5 said partition and into said chamber for at times melting ice from said coils, washing said air, carrying moisture into said chamber and producing a uniform condition of temperature and humidity in said chamber and chronometric means for 10 starting and stopping the operation of said means at regular intervals.

3. In combination with a chamber of comparatively large size, a partition adjacent one wall of said chamber and spaced from the top and bottom thereof and a plurality of refrigerating coils between said wall and partition to which a cooling medium is intermittently supplied to maintain substantially a certain temperature in 15 said chamber, a casing adjacent the top of said chamber having open ends, one end of said casing

being directed toward said coils, a fan in said casing for directing air therethrough and downwardly over said coils and means for starting and stopping said fan at regular intervals.

4. The method of controlling the atmosphere 5 in a refrigerating room having cooling coils therein to which a cooling medium is intermittently supplied by a device controlled by the temperature in said room, which consists in circulating the air in said room and directing said moving 10 air over said coils, said operation being alternately continued for a certain definite time period and then discontinued for a certain definite time period so that the same is intermittent and acts at times to remove ice or frost from said coils, and 15 acts to maintain an atmosphere in said room with the temperature and a high humidity substantially uniform in all portions of said room.
